UNITED STATES PATENT OFFICE.

EDMUND W. WILEY, JR., OF LECOMPTÉ, LOUISIANA.

HOISTING TRIP AND SLING.

SPECIFICATION forming part of Letters Patent No. 617,267, dated January 3, 1899.

Application filed March 11, 1898. Serial No. 673,537. (No model.)

To all whom it may concern:

Be it known that I, EDMUND W. WILEY, Jr., a citizen of the United States, residing at Le-
compté, in the parish of Rapides and State of
Louisiana, have invented a new Hoisting Trip
and Sling, of which the following is a specific-
cation.

This invention relates to certain new and
useful improvements in slings for elevating
hay, cane, &c., having for its object to pro-
vide simple and effective means for the pur-
pose whereby the sling may be quickly se-
cured around a load to be lifted and which
may be released from the load with equal fa-
cility to permit it to be deposited at the de-
sired point.

It is also an object of the invention to pro-
vide a sling which may be secured around a
load after it has been placed upon a wagon,
thereby obviating the necessity of employing
a separate sling for each wagon in use.

With this object in view the invention re-
sides in the novel construction and arrange-
ment of the parts hereinafter more particu-
larly described.

In the accompanying drawings, forming a
part of this specification, and in which like
letters and numerals of reference designate
corresponding parts, Figure 1 is a side eleva-
tion of apparatus embodying the invention.
Fig. 2 is a detail view of a portion of the trip-
beam and latch-frame. Fig. 3 is an end view
of the apparatus, showing the parts in the po-
sitions they occupy when supporting a load;
and Fig. 4 is a similar view of the parts when
disconnected from a load.

Referring more particularly to the draw-
ings, A designates a trip-beam, and B an aux-
iliary beam, each of which is supported upon
tie-rods 1 2, respectively, which rods prefer-
ably converge upwardly to a suitable device,
in the present instance in the form of a ring
3, by means of which the sling is connected
to any desired elevating mechanism. The
tie-rods 1 2 are loosely connected with the
ring 3 in order to permit their beams A B to
swing laterally with respect to each other,
thereby enabling them to be adjusted to
planes upon opposite sides of that occupied
by the ring 3. At their lower ends the tie-
rods 1 are formed substantially T-shaped, the

lateral projection at said ends being received
in separated sockets 4 at one of the lower
side edges of the beam A and constituting
pivot points upon which the beam is per-
mitted to swing.

Supported rigidly upon the tie-rods 1 at a
point intermediate the ring 3 and the beam
A is a beam 5, upon which is pivotally sup-
ported the upper end of a latch-bar 6, and a
spring 7 is likewise connected to said beam
and to the latch-bar, the tendency of said
spring being to carry the said bar into en-
gagement with the slot of a latch 8. This
latch is carried upon a frame 9, connected to
and extending from the beam A, and the ef-
fect of the engagement of the latch-bar 6 with
the latch 8 is to prevent the beam from swing-
ing downwardly upon its pivots. A rope or
chain 10 is connected to the lower end of the
latch-bar, by means of which it may be drawn
out of engagement with its latch when it is
desired to release the trip-beam A.

Arranged at separated points along the
length of the trip-beam A are pairs of angle-
irons 12, which extend around one side and
over the top of the beams and terminate at
their upper and lower ends in sockets 13 14,
respectively.

The sockets 13 are normally in planes be-
low the lower edges of the trip-beam and be-
low that of its pivotal points, while the sock-
ets 14 are above the plane of said pivotal
points and preferably above that of the up-
per edge of the trip-beam. Pivotally sup-
ported within the sockets 13 14, respectively,
are hooks 15 16, and carried upon the auxil-
iary beam B is a series of separated hooks 17.
Connected at its opposite end to the hooks
16 17 is a flexible sectional sling rope, chain,
or cable C, which in the present instance is
formed of two sections 18 19, although in some
instances said sling-rope may be formed of a
greater number of sections, if desired, and
the said sections may be of any suitable
length, depending, of course, upon the diam-
eter of the load they are to surround. At
their meeting ends the sling-rope sections are
adapted to be connected together and discon-
nected from each other, and as a simple and
convenient means of effecting this the end of
one section—as, for instance, the section

19—is provided with a ring 20, adapted to be engaged by a hook 21, pivotally supported at the end of the section 18.

Means are provided for automatically releasing the sling-rope C from around the load, and while various devices may be employed for effecting this function those which will now be described are preferred on account of their simplicity and effectiveness, the said devices being actuated by the weight of the load carried by the sling.

Connected to an arm 22 of the hook 21 is a hook-releasing line 23, which extends upwardly and is connected to the hook 15, this line being so arranged that when pulled upon it will swing the hook 21 upon its pivot and withdraw it from engagement with the ring 20, thereby disconnecting the sling-rope sections. It will be understood, of course, that a series of sling-ropes C is employed, one sling-rope being provided for each pair of hooks 16 17.

With the parts thus constructed and arranged, when it is desired to lift a load (indicated by dotted lines, Fig. 3) the trip-beam A is latched in its elevated position at one side of a vertical pin passing centrally through the load, and the auxiliary beam B is arranged upon the opposite side of said line. The sling-rope sections are then passed around the sides and beneath the load and the hook 21 is secured into the ring 20. The load is then elevated and carried to the desired point by suitable means connected with the ring 3. The latch-bar 6 is then disengaged from the latch 8 by pulling upon the chain 10. This leaves the trip-beam A free to swing downwardly to the position shown in Fig. 4, to which position it is carried by the weight of the load. In moving to this position the hook 16 is lowered, slackening the tension upon the sling-rope section 18, while the hook 15 is carried upwardly, tightening the rope-section 23, which causes the hook 21 to be pulled out of engagement with the ring 20, disconnecting the sections 18 19 and allowing the load to drop out of the sling.

From the above description it will be obvious that a simple and effective sling is provided, capable when not in use of being folded up in a small space, and one which may be adjusted about a load while it is upon a wagon or other structure, thus possessing a great advantage over those slings which have to be placed upon the wagon before loading the same. While I have described and shown an auxiliary beam B, it will be obvious that this may be dispensed with and the sling-rope section 19 connected directly to the tie-rods 2, or the tie-rods and beam B may both be dispensed with and the rope 19 connected di-

rectly to the ring 3. These and various other modifications in the construction and arrangement of the parts might be made without departing from the spirit or scope of the invention, since

What I claim is—

1. A hay-sling comprising a pivoted trip-beam, sectional sling-ropes adapted to be secured around a load, locking devices for securing the ends of the rope-sections together, means for holding the trip-beam against movement and for releasing it to permit it to turn upon its pivot, and positive connections intermediate the trip-beam and the locking devices of the rope-sections for actuating the locking devices to disconnect said sections upon the turning of the trip-beam, substantially as described.

2. A hay-sling comprising means for attaching it to elevating mechanism, a pivoted trip-beam connected to the attaching means, locking devices for preventing the swinging of the beam upon its pivot, means for releasing the locking devices, flexible hay-sling ropes adapted to be secured around the load to be lifted and devices actuated from the swinging beam for releasing the sling-ropes from the load, substantially as described.

3. A hay-sling comprising sectional locking devices, two series of flexible sling-ropes, the ends of each series of ropes being disconnected and the ends of one series carrying one section of a locking device adapted to engage with a second section of the locking device carried at the ends of the second series of sling-ropes, and automatic means dependent for their actuation upon the weight of a load for disengaging the sections of the locking devices to release the sling-ropes from the load, substantially as described.

4. A hay-sling comprising means for attaching it to elevating mechanism, a pivoted trip-beam supported upon the attaching means, devices for locking the beam against and for unlocking it to permit it to swing upon its pivot, sectional, flexible sling-ropes adapted to be secured around a load to be elevated and connected at one end to the trip-beam above its pivotal points, locking devices connecting the ends of the sling-sections together, flexible lines connecting said locking devices with the trip-beam at points below the plane of its pivotal point whereby the locking devices are actuated to uncouple the sling-sections upon the swinging of the beam upon its pivot, substantially as described.
